SEWING MACHINE

Albert W. Bradbury, Cliftondale, and Roy E. Hood, Lynn, Mass., assignors to United Shoe Machinery Corporation, Paterson, N. J., a corporation of New Jersey

Application February 8, 1934, Serial No. 710,238

6 Claims. (Cl. 112—45)

The present invention relates to improvements in channel forming and work guiding devices for McKay type shoe sewing machines employing waxed thread and comprising a straight hook needle, a rotary horn arranged to extend within and support the shoe, and a needle threading whirl located within the horn.

The object of the invention is to provide in a sewing machine of the McKay type, a simplified and improved means for cutting a stitch receiving groove of uniform depth in the work.

With the above and other objects in view, a feature of the present invention contemplates the provision in a McKay type shoe sewing machine having a work supporting horn, a straight hook needle, a presser foot and a feed point, of a work channelling knife acting in the line of feed between the needle and the presser foot to form a stitch receiving groove in the side of the work opposite the horn. In the embodiment described, the work channelling knife is provided with one or more laterally extending shoulders to engage the surface of the work and cause the knife to cut a channel of uniform depth, the work being first compressed by the presser foot and subsequently by the shoulders on the knife to prevent irregularities. As illustrated, the cutting is accomplished by means carried by the feed point, so that the extending shoulders act to render more effective the operation of the feed point in feeding the work by preventing the formation of irregular projections on the surface of the work. By the provision of lateral shoulders on the feed point, not only is the feeding movement itself improved, but the channelling knife being attached to the feed point to cut during movement of the feed point towards the work, does not cause any displacement of the work in the line of feed and maintains the surfaces at the sides of the channel substantially smooth and undisturbed.

Other features of the invention consist in certain constructions, arrangements and combinations of parts, the advantages of which will be obvious to those skilled in the art from the following description.

In the drawing, Figure 1 is a view in front elevation of a portion of a sewing machine embodying the present invention, parts being broken away and shown in section; Figure 2 is a view in front elevation on an enlarged scale of the work engaging portion of the combined feed point and channelling knife embodying the invention; Figure 3 is a view in end elevation of the knife shown

in Figure 2; and Figure 4 is a bottom plan view of the knife.

The machine illustrated in the drawing comprises a straight hook needle 10, a rotary work supporting horn 12, a presser foot 14, a rotary shuttle 16, a loop spreader 18 and other mechanisms for forming a lockstitch seam. The presser foot is actuated alternately to clamp and release the work, indicated at 19, and the work is fed while released from the presser foot as is usual in this type of machine, an example of which is illustrated and described in the U. S. patent to Ashworth No. 1,914,936 granted June 20, 1933.

In the illustrated machine, as in the machine of the Ashworth patent, the work is fed by a feed point secured in a carrier indicated in the drawing of the present application at 20 which is moved towards and from the work to cause the tip of the feed point to engage and disengage the work in the line of feed between the needle and the presser-foot. The connections for engaging and disengaging the feed point include a link 22 and a bell crank lever 24 connected between the presser foot actuating mechanism and the feed point carrier 20 for limiting the depth to which the feed point is permitted to penetrate the work. The feeding movements of the feed point are produced by swinging the carrier 20 between the needle and the presser foot, and are so adjusted that the needle will penetrate the work at points coinciding with indentations formed by the feed point, so that slight variations in the depth to which the feed point penetrates causes no difficulty in the finished seam.

According to the present invention the feed point, indicated at 26, of the present machine is formed with a work channelling knife edge 28 acting in the direction of feed directly behind the presser foot so that the presser foot serves to smooth the surface of the work to a certain extent before the channelling knife forms its groove. To prevent any variation in the depth to which the feed point and channelling knife may penetrate, the point is provided with laterally extending shoulder portions 30 having flat under surfaces to engage and compress the work at either side of the channelling knife 28. The knife 28 is formed with its cutting edge extending horizontally to cut the work during the downward movement of the feed point, the feeding movement taking place after the shoulders 30 have been seated on the work surface. To insure proper feeding action, a downwardly extending tip 32 may be formed at the forward

end of the knife portion 28. The shoulders 30 on the feed point not only cause the knife to form a groove of uniform depth but also act to compact the material operated upon firmly about 5 the tip 32 so that during the feeding movement, a better grip on the work will be maintained. With the arrangement described, the type of machine illustrated in the Ashworth patent referred to may be equipped with a channelling 10 knife with no additional mechanical changes aside from possibly a slight adjustment to compensate for the different reaction on the feed point caused by increased resistance against downward movement of the channelling knife.

15 Having thus described the invention, what is claimed is:

1. A sewing machine of the McKay type having, in combination, stitch forming and work feeding devices including a straight hook needle, 20 a rotary work supporting horn, a presser foot for alternately clamping and releasing the work supported by the horn, a feed point acting on the side of the work engaged by the presser foot to feed the work when released by the presser 25 foot, and a knife operating in the line of feed between the needle and the presser foot to form a stitch receiving groove in the work.
2. A sewing machine of the McKay type having, in combination, stitch forming and work 30 feeding devices including a straight hook needle, a rotary work supporting horn, a presser foot for alternately clamping and releasing the work supported by the horn, a feed point acting on the side of the work engaged by the presser foot 35 to feed the work when released by the presser foot, a knife operating in the line of feed to form a stitch receiving groove in the work, and means carried by the knife for engaging the work to limit the depth of the groove.
- 40 3. A sewing machine of the McKay type having, in combination, stitch forming and work feeding devices including a straight hook needle, a rotary work supporting horn, a presser foot for alternately clamping and releasing the work supported by the horn, a feed point acting on the side of the work engaged by the presser foot 45 to feed the work when released by the presser foot, a knife operating in the line of feed between the needle and the presser foot to form a

stitch receiving groove in the work, and a lateral extension on the knife for engaging the surface of the work to limit the depth of the groove.

4. A sewing machine of the McKay type having, in combination, stitch forming and work feeding devices including a straight hook needle, a rotary work supporting horn, a presser foot for alternately clamping and releasing the work, a feed point movable towards and from the side of the work engaged by the presser foot and in the line of feed to feed the work when released by the presser foot, a knife connected to the feed point to form a stitch receiving groove in the work as the feed point moves towards the work, and a lateral extension on the knife for engaging the surface of the work to limit the depth of the groove.

5. A sewing machine of the McKay type having, in combination, stitch forming and work feeding devices including a straight hook needle, a rotary work supporting horn, a presser foot for alternately clamping and releasing the work, a feed point movable towards and from the side of the work engaged by the presser foot and in the line of feed to feed the work when released by the presser foot, a knife connected to the feed point to form a stitch receiving groove in the work as the feed point moves towards the work, and a lateral extension on the knife at either side of the cutting edge for engaging the surface of the work on both sides of the line of stitching to limit the depth of said groove.

6. A sewing machine of the McKay type having, in combination, stitch forming and work feeding devices including a straight hook needle, a rotary work supporting horn, a presser foot for alternately clamping and releasing the work supported by the horn, a feed point movable towards and from the side of the work engaged by the presser foot and acting in the line of feed between the needle and the presser foot to feed the work when released, a knife connected to the feed point to form a stitch receiving groove in the work as the feed point moves towards the work and a lateral extension on the knife for engaging the surface of the work at one side of the groove to limit the depth of the groove.
